John Harness

ATTORNEY.

UNITED STATES PATENT OFFICE

GEORGE W. MASON, OF DETROIT, MICHIGAN, ASSIGNOR TO COPELAND PRODUCTS, INC.,
OF DETROIT, MICHIGAN, A CORPORATION OF MICHIGAN

REFRIGERATOR CABINET

Application filed May 8, 1926, Serial No. 107,578. Renewed May 5, 1930.

My invention relates to refrigerator cabinets which are cooled by the evaporation of a liquid refrigerant or like process and particularly to cabinets in which refrigerating machines are installed and built as a unit.

The combination of a refrigerator cabinet and refrigerating machine is not new; however, in existing constructions of this nature the refrigerating unit is not as easily detachable or accessible for adjustment and repairs as it should be.

The objects of this invention are to combine a refrigerator cabinet and refrigerating unit in such a manner that the refrigerating unit which includes the motor, compressor, condensing coils and expansion coils and their connections, may be quickly and easily removed in its entirety from the refrigerator cabinet, and replaced by another like unit when it is necessary to adjust, repair or replace the old refrigerating unit, and thus provide for the continuous and uninterrupted use of the refrigerator.

With these and other objects in view, my invention consists in the arrangement, combination and construction of the various parts of my improved device as described in the specification, claimed in my claims and shown in the accompanying drawing, in which:

Fig. 1 is a vertical section of a refrigerator cabinet, showing the refrigerating unit installed and in position for operation.

Fig. 2 is a cross section of the cabinet taken on line 2—2 of Fig. 1.

Fig. 3 shows a modification of my device for supporting the expansion coil of the refrigerating unit within the cabinet.

I have shown in Fig. 1 a cabinet having conventionally insulated walls 1 and a removable cover 2.

The refrigerating machine or unit illustrated, is of the conventional type employing the compressor 3 driven by the motor 4 to deliver the refrigerant to the condenser 5 which is cooled by the atmosphere. The refrigerant is delivered from the condenser 5 by the pipe 6 to the expansion coil 7 and is there gasified and then delivered to the

compressor 3 by the pipe 8. The motor 5, the compressor 3 and the condensing coil 5 are all mounted upon and supported by the base 9,—the expansion coil 7 being attached thereto. The base 9 is constructed to fit within the walls 1 of the cabinet, and is supported therein by angle brackets 10 which are attached to the inner sides of walls 1 as shown. The inner space of the cabinet is divided into an upper and a lower compartment by an insulated transverse partition 11 which completely separates the lower or cooling compartment from the upper compartment which contains the motor, compressor and condensing coils of the refrigerating unit. The expansion coil 7 of the refrigerating unit is positioned below the transverse partition 11 and within the cooling compartment, and is supported therein by the brackets 12, the said brackets being pivotally attached to the underside of the partition 11 and adapted to swing into contact with, and support expansion coil 7 or to swing away from expansion coil 7, as indicated by the dotted lines, and so release said expansion coil 7 for removal. The partition 11 is cut away in the center to provide a circular opening 13 of sufficient size to permit the insertion of expansion coil 7, there being provided in one side of said opening, slots or channels, as indicated by numeral 14, in Fig. 2, of sufficient size to permit the passage of pipes 6 and 8. A removable plug or cover 15 with overlapping upper edges, is provided to fill and completely close the opening 13 in partition 11 and will, when in place, prevent any circulation of air currents between the upper and lower compartments of the cabinet. The pipes 6 and 8, when in place in the channel 14, may be packed with any suitable packing material to prevent the passage of air currents through the partition 11.

In Fig. 2 I have shown a plan view of the upper side of partition 11, taken on line 2—2 of Fig. 1.

In Fig. 3 I have shown expansion coil 7 supported by an open-work metal partition 16 which is so constructed as not to interfere with the flow of air currents in the

lower compartment of the cabinet, and is attached to the inner sides of walls 1 by angle brackets 17, or other suitable means. The support 16 is a modification that may be used, if desired, in preference to supporting brackets 12 as shown in Fig. 1.

When it is necessary to repair, adjust or replace the refrigerating unit, the cover 2 of the cabinet may be removed, and the 10 cover 15 in opening 18 of the partition 11 may be removed, the brackets 12 swung back from contact with the expansion coil 7, and the entire refrigerating unit mounted upon the base 9 and including the expansion coil

15 7 may be lifted out of the cabinet, thereby obtaining access to any and all of its parts, and the whole may be at once replaced by another unit of like kind, if that is desired, or the cover 15 replaced without inserting 20 another refrigerating unit, thus conserving the cold in the cabinet. In some cabinet constructions it would be possible to use the same by the insertion of ice after the unit had been removed.

25 It will be obvious that various changes may be made in the arrangement, combination and construction of the various parts of my improved device without departing from the spirit of my invention, and it is my intention to cover by my claims such changes as may be reasonably included within the 30 scope thereof.

What I claim is:

1. The combination of a refrigerator cabinet having an insulated, apertured horizontal partition therein, an expansion chamber insertible through said aperture, support members on the vertical walls of the cabinet above said partition, a base mounted on said 35 40 support members, a motor, compressor and condenser mounted on said base, connections through the aperture in said partition joining the expansion chamber to the compressor and condenser and means for removably 45 closing said aperture.

2. In a refrigerator cabinet, the combination of the side walls thereof, an insulated horizontal partition having an opening therein positioned between said walls, a base 50 55 positioned horizontally above said partition, and removably attached to the side walls of said cabinet, a motor, a compressor and condenser mounted upon said base, an expansion chamber suspended beneath said base and insertible through the opening in said partition, pipes extending through said partition for connecting said expansion chamber with said compressor and said condenser, hooks pivotally attached to the under side 60 65 of said partition for supporting said expansion chamber, and a removable closure for said opening in said partition.

3. The combination of a refrigerator cabinet having an insulated horizontal partition 66 therein dividing said cabinet into two com-

partments, said partition having an opening therein, an expansion chamber insertible through said opening, means for supporting said chamber with the lower compartment of said cabinet beneath said partition comprising a plurality of hangers hingeably suspended from the under side of said partition and removably engaged with said chamber, a motor, compressor and condenser mounted above said opening, connections extending through said partition for joining the expansion chamber with the condenser and compressor and a removable closure for said opening in the partition.
